H. S. WHITE.

PACKING FOR ROTARY ENGINES AND COMPRESSORS.

APPLICATION FILED DEC. 29, 1919.

1,409,986.

Patented Mar. 21, 1922.

UNITED STATES PATENT OFFICE.

HENRY S. WHITE, OF CHICAGO, ILLINOIS, ASSIGNOR, BY MESNE ASSIGNMENTS, TO AMERICAN ROTARY ENGINE CO., OF GRAND RAPIDS, WISCONSIN, A CORPORATION OF WISCONSIN.

PACKING FOR ROTARY ENGINES AND COMPRESSORS.

1,409,986.

Specification of Letters Patent. Patented Mar. 21, 1922.

Original application filed February 25, 1918, Serial No. 219,040. Divided and this application filed December 29, 1919. Serial No. 348,166.

To all whom it may concern:

Be it known that I, HENRY S. WHITE, a subject of the King of Great Britain, residing at Chicago, in the county of Cook and State of Illinois, have invented a new and useful Improvement in Packings for Rotary Engines and Compressors, of which the following is a specification.

My invention relates to an improved form of packing for the rotary piston or inner element in a device of the class comprised of rotary engines, compressors and the like where the inner element which may be called a rotor or piston moves relatively to an enclosing casing under the action of fluid under pressure or for the purpose of compressing or pumping fluid and the like. By my invention I provide an improved means by which the outer surface of the rotor or inner member may be made fluid tight relatively to the inner surface of the casing and also means by which the end walls of the inner member may be made fluid tight relatively to the end walls of the casing.

This is a divisional application of my copending application Serial No. 219,040, in which application a novel form of compressor is described, shown and claimed. My present application is therefore limited to the packing device employed and I show in the present application a simple form of compressor substantially the same as the disclosure in my above application mentioned, it being understood that this complete machine is simply illustrated as a device in which my packing may be used and I do not limit myself to the use of said packing either in compressors or rotary engines but that on the other hand the packing is of use in connection with any device of the nature shown in this case where it is desirable to pack the ends or outer surface or both, of the inner member.

My invention will best be understood by reference to the accompanying drawings showing a preferred embodiment thereof, in which

Fig. 1 shows a compressor in transverse sectional view to show the packing device

in place on the inner member of said compressor. 50

Fig. 2 shows the packing elements employed in side elevation as they would appear in assembled relation, removed from the inner element of the compressor. 55

Fig. 3 is an enlarged sectional view taken longitudinally of the compressor through the lower part of the inner element and outer element along the line 3—3 in Fig. 1 to show the construction and location of the packing elements on the inner member of the compressor, and 60

Fig. 4 shows in a view similar to Fig. 3 a modified construction of inner member permitting the use of part of my packing devices to accomplish the function intended of packing the ends of the inner member against the corresponding end walls of the construction. 65

Similar numerals refer to similar parts throughout the several views.

The construction of the compressor shown in the drawings, which is substantially the same as shown in my co-pending application referred to, consists of a cylindrical casing 75 having end walls 1 and a cylindrical shell 2 bored internally to engage the cooperating parts contained in the casing. The casing has projecting inwardly and radially from its outer wall a diaphragm 4 which is rigidly secured to the casing. A rotor 5 is disposed eccentrically in the casing and consists of a cylindrical member mounted on a suitable shaft 6. The rotor 5 is provided with a recess for receiving the diaphragm 4 and suitable guide plates 8 and 9 mounted on either side of the diaphragm supported upon bearing pins or rods 16, which construction permits a slight degree of angular motion of the diaphragm relatively to the rotor as the device is operated. The shaft 6 and the ends of the compressor are provided with suitable bearings not shown for supporting the parts to maintain the eccentric relation shown in Fig. 1 and in the particular construction of the device illustrated in the drawings both the casing and the rotor are arranged to rotate in the direction of the 90

95

arrow by suitable means as a result of which the compartments 10 and 11 on either side of the diaphragm 4 are increased and decreased in size to draw in air through the port 18 and expel it through the port 20 and check valve 22. The port 18 communicates with a bore 19 in one end of the shaft 6 and the chamber of the valve 22 at its inner end communicates by a passageway 23 with a bore 24 through the other end of the shaft 6, the bores in the shaft being separated from each other.

The relation between the rotor and the casing is such that the rotor is practically in contact with or tangent to the inner cylindrical surface of the casing along the lower longitudinal element of the rotor, being separated therefrom slightly to prevent friction and wear. To prevent leakage of the air under pressure from the compartment 11 to the compartment 10, I provide packing devices between the rotor and the casing as follows: the end faces of the rotor just clear the inner end faces of the casing and in the outer edges of the end faces of the rotor grooves are formed to receive packing rings 12, and within these grooves additional grooves are formed to receive triangular or equivalent packing rings 13 of metal which are in the form of expansion rings of the kind ordinarily employed as piston rings with the exception that the cross section of the rings is triangular instead of rectangular and in the construction shown the base of the triangular cross section is innermost so that the hypotenuse of the triangular section rests against the corresponding face of the groove formed in the rotor. The vertical face of each packing ring 13 is in contact with the inner vertical face of the ring 12 as a result of which the tendency of the ring 13 to expand acting upon the triangular face of its containing groove exerts pressure longitudinally of the rotor against the packing ring 12 thus tending to move it against the corresponding end wall of the casing and in this manner fluid tight joints are made between the ring 12 and the end of the casing, between the ring 13 and the packing ring 12 and also between the ring 13 and the rotor 5. As a result of the outward movement of the packing ring 12 by the triangular ring 13 in the manner described, there is a slight clearance between the inner faces of the ring 12 and the vertical faces of the grooves containing them in the rotor which would permit fluid to pass the tangent point between the rotor and the casing were there no additional means to prevent it. To prevent this leakage and also to prevent leaks around the cylindrical surface of the rotor at the point referred to, I provide a plurality of baffle bars 14 which extend longitudinally of the rotor on its cylindrical surface, these

bars being of T-shaped cross section and contained in slots in the cylindrical face of the rotor which are of corresponding cross section. The slots for the bars 14 in the rotor are of such a size as to permit radial movement only of the bars in the rotor so that the outer surfaces of the bars will come positively into engagement with the cylindrical surface of the casing as the rotor passes the tangent point. The slots in the rotor are sufficiently deep so that this action takes place without bottoming of the bars in the slots at the time of passing the tangent point and I find that rotation of the device keeps the bars in their outermost position by the centrifugal action of the bars, as a result of which there are always several of the bars in contact with the inner cylindrical surface of the casing as the tangent point is passed in the operation of the device. As shown in Fig. 3 the relation between the triangular expansion ring 13 and the bars 14 is such that the outer edge of said ring extends slightly beyond the head of the T-shaped portion on each bar, as a result of which the portion of each bar which extends from the expansion ring 13 outwardly is of rectangular cross section through a corresponding slot formed to receive the same in the packing ring 12. In this manner although the bars 14 are slightly shorter than the longitudinal dimension between the inner vertical faces of the casing, the packing ring 12, the triangular expansion ring 13 and the bars 14 cooperate to pack the joints between the rotor and the casing both on the cylindrical exterior surface of the rotor and the end surfaces of the same.

In some cases as for example where it is not required to use the device in connection with high pressure, a slightly modified construction is effective consisting in providing the rotor 5^a with triangular grooves in its ends for containing the triangular expansion rings 13 without making use of the packing rings 12 or the bars 14, as shown in Fig. 4. In this case the action of the triangular rings is substantially the same as above described the only difference being that their outer faces bear directly against the inner faces of the casing. In this case the parts are so disposed that the outer cylindrical surface of the rotor 5^a is in contact with the inner cylindrical surface of the casing at the point of tangency above referred to. In either of the cases above described it will appear that the centrifugal force exerted upon the triangular packing rings tends to increase the effect of their outward expansion to seal the joints between the rotor and the casing.

It will be understood that while I have shown my packing as used in connection with a compressor of the kind described it

may be used with any similar type of device in which there is an inner element having a relative lateral movement in an enclosing casing, regardless of the manner in which 5 the lateral movement is produced, and regardless also of whether the device is constructed to be used as a compressor or as a prime mover.

While I have shown my invention in the 10 particular embodiment above described, it will be understood that I do not limit myself to this exact construction in carrying out my invention, as I may employ equivalents known to the art at the time of the 15 filing of this application without departing from the scope of the appended claims.

What I claim is:

1. A packing for a cylindrical member comprising an end packing ring, longitudinal baffle bars ending at said ring, and an 20 expansion ring engaging said packing ring adjacent the ends of said bars to exert an outwardly directed side thrust on said packing ring.

2. A packing for a cylindrical member comprising an end packing ring, longitudinal baffle bars ending at said ring, and an 30 expansion ring engaging said packing ring adjacent the ends of said bars to exert an outwardly directed side thrust on said packing ring, said packing ring having radial slots fitting the ends of said bars.

3. A packing for a cylindrical member comprising an end packing ring, longitudinal baffle bars ending at said ring, and an 35 expansion ring engaging said packing ring adjacent the ends of said bars to exert an outwardly directed side thrust on said packing ring, said bars packing the outer cylindrical surface of said member and the inner 40 face of said packing ring.

4. A packing for a rotary cylindrical member having longitudinal slots of T-shaped cross section in its cylindrical surface 45 comprising baffle bars of similar cross section fitting said slots circumferentially and having play in said slots radially, whereby the centrifugal action upon said bars due to their rotation moves them outwards to 50 packing position.

5. A packing for a rotary cylindrical member having longitudinal slots in its cylindrical surface comprising baffle bars of similar cross section to said slots fitting said

55 slots circumferentially and having play in said slots radially and means for limiting outward movement of said bars in said slots to a radial position slightly farther out than their packing position, whereby the centrifugal force exerted on said bars holds them in packing position.

6. A packing for a device having a hollow casing with substantially parallel inner end surfaces and an inner member having

substantially parallel end walls adjacent 65 said inner end surfaces and adapted to movement laterally in said casing comprising end packing rings of metal to be carried by said member to engage said inner surfaces and split metal rings to be carried by said member between it and said packing rings, said 70 split rings being restrained radially when in place and tending to move said packing rings apart.

7. A packing for a device having a hollow casing with substantially parallel inner end surfaces and an inner member having substantially parallel end walls adjacent said 75 inner end surfaces and adapted to movement laterally in said casing comprising end packing rings of metal to be carried by said member to engage said inner surfaces and split triangular metal rings to be carried by said member between it and said packing rings, said 80 split rings being restrained radially when in place and tending to move said packing rings apart.

8. A packing for a device having a hollow casing with substantially parallel inner end surfaces and an inner member having 85 substantially parallel end walls adjacent said inner end surfaces and adapted to movement laterally in said casing and having end grooves with outwardly diverging end walls comprising flat end packing rings of metal 90 and split metal rings engaging said packing rings and having inner outwardly diverging edge surfaces, said split rings being restrained radially when in place and tending to move 95 to move apart.

9. A packing for a device having a hollow cylindrical casing with substantially parallel inner end surfaces and an inner cylindrical member having substantially parallel end walls adjacent said inner end surfaces and adapted to movement laterally in 100 said casing and having longitudinal grooves in its cylindrical surface and end grooves comprising baffle bars fitting said longitudinal grooves circumferentially and having 110 limited motion therein radially, metal packing rings and split metal rings for placement in said end grooves, said bars engaging said packing rings and said split rings engaging said packing rings and having inclined edge faces and restrained when in place and tending to move said packing rings apart.

10. A packing for a device having a hollow cylindrical casing with substantially 120 parallel inner end surfaces and an inner cylindrical member having substantially parallel end walls adjacent said inner end surfaces and adapted to movement laterally in said casing and having longitudinal 125 grooves in its cylindrical surface and end grooves having outwardly diverging edge surfaces comprising baffle bars of T-shaped

cross section fitting said longitudinal grooves circumferentially and having limited motion therein radially, flat metal packing rings and split metal rings for placement in said end grooves in engagement with said flat rings, said split rings having outwardly diverging inner edge surfaces and tending

when in place to move outwards radially and from each other to move said flat rings apart.

In witness whereof, I hereunto subscribe my name this 20th day of December, A. D. 1919.

HENRY S. WHITE.
